UNITED STATES PATENT OFFICE

2,006,523

POWER GENERATING SYSTEM

Chester F. Strong, Miami, Fla.

Application July 16, 1932, Serial No. 622,967

5 Claims. (Cl. 290—30)

This invention relates generally to power generating equipment utilizing internal combustion engines and has particular reference to improved control equipment for starting or stopping a plurality of units either entirely by manual control or entirely automatically or by a combination of the two.

One object of my invention is to provide an improved control system whereby the various automatic or manual control functions may be effected with equal facility either alone or together and in such a manner that when only a part of their respective functions are selected they will be coordinated without interference from the remaining unused functions.

A further object is to provide an improved arrangement for using the generators as motors to start their respective engines which are preferably of the Diesel type and yet reducing to a minimum dangers from a short circuit in case the engines fail to start under predetermined conditions of operation.

Another object is to provide an improved arrangement for insuring, without temporary adjustment, substantially normal voltage when a unit is brought onto the line. If any temporary adjustment is necessary to compensate for briefly existing inherent characteristics it would be particularly troublesome in a power plant for which my invention is especially adapted, my equipment being used preferably in apartment houses, hotels, office buildings, etc. wherein sudden loads are thrown on the line such as elevator motors, etc. thereby quite often necessitating the starting of a unit and running it only temporarily to carry the elevator load. It is thus seen that if temporary adjustments must be made then if these adjustments are made by an attendant the full value of the economical operation of automatic control is lost because of the cost of the attendant's labor. It is an object of my invention to provide improved means for not only taking care of this matter automatically but of simplifying as far as possible the manner in which it is taken care of. Specifically it is an object of my invention to eliminate a cause of voltage control difficulty experienced in automatic apparatus of the kind herein disclosed by providing a relatively simple arrangement which eliminates the necessity of having automatic devices for compensating for the voltage variations created by the otherwise existing cause. The difficulty referred to is that in a building using my plant, an engine may be idle for a sufficient length of time so that its generator becomes cold whereby when the engine is started the generator will gradually become warm with a consequent variation in voltage over that of the cold generator. In my improved arrangement I have embodied as part of the automatic equipment suitable means whereby

the generator at all times will be maintained at or sufficiently near its normal operating temperature to avoid the voltage fluctuations which would otherwise occur.

A further object is to provide an improved arrangement for starting the units by motor action of the generator in combination with a battery, battery booster and means whereby starting current for the motors is obtained without current being taken through the armature of the booster, and yet voltage control is effected by the battery booster.

Other objects and advantages will be more apparent from the following description of the accompanying drawing which is a wiring diagram of my improved system embodying diagrammatic illustrations of the mechanical elements.

In the accompanying drawing, A, B and C represent generating units employing internal combustion engines, preferably of the Diesel type, driving electric generators. A constant source of current supply, such as a supplemental or standby source of current herein specifically shown in the form of an electric storage battery 1 is connected directly to mains 2 and 3. This source serves not only as an auxiliary source for starting the units but in addition is adapted to supply a certain regular line load. In this regard the source can be a constantly operating engine although a battery is preferable for several reasons including a smoother and more dependable degree of cooperation between all of the elements. In the case of the battery it is connected directly to mains 2 and 3 through a booster 4 which is driven by a motor 5.

Two methods of starting the generating units are shown herein and these are coordinated in an improved manner. In one, compressed air is stored in a receiver or tank 6 which is supplied by an air compressor 7 adapted automatically to maintain the desired pressure. Air valves 8 are located in pipe lines 6a leading from the tank to supply each engine with compressed air as through distributor valves 9 and pipes 10, pipes 10 being omitted from units B and C for clearness. When starting an engine with compressed air, a switch 11 is closed so that compression relief mechanisms 12 will remain closed and prevent escape of starting air. A lever 13 of a fuel pump 14 is raised from a stop 15 and a latch 16 placed under lever 13 so as to permit fuel pump 14 to inject fuel into the cylinders. When arm or lever 13 is down against stop 15 the arm causes fuel oil to be either cut off or by-passed from fuel pumping mechanism 14 so that fuel is not injected into the cylinders. When engine A has started and reached the proper speed it is assumed any usual governing mechanism, not shown, controls the operation of fuel pump 14 in such a manner that just sufficient fuel is sup-

plied to the engine to enable it to maintain the correct speed for the load. The air valve 8 is of course manually closed when the engine starts.

Assuming that generating unit A has been started by closing its switch 11 and using starting air through its air valve 8 as just described, then as the engine comes up to speed switch 16' is manually closed causing switching mechanism, to be described, to place the generating unit on the line. This switching mechanism will not permit the generator to be connected with the load line unless the generator voltage is set correctly, the switching mechanism having the further function of opening the connection from the generator to the line and also for automatically shutting down the engine in case the unit becomes out of order.

The control of the switching mechanism is as follows: Closing of switch 16' allows current to flow from line 2 through wires 17, 17' to switch contact 18, spring 19, wires 20 and 21, solenoid coil 23 which closes switch 22, thence through wire 23' and closed contacts 68 of a deenergized solenoid 64 to the other line 3. Closure of switch 22 is then followed by automatic connecting of the unit to the line only if the generator voltage is normal, this being in a manner to be presently described for the full automatic control operation.

After the engine has been started by manual operation and its generator connected to the line, if for any reason the unit becomes inoperative the generator will take current from the line and hence begin to act as a motor. Assuming the unit to be inoperative the motoring of the engine should be stopped only after the motoring action has continued for a predetermined period of time, it being desirable not to stop the unit immediately when it becomes inoperative because the inoperative condition may only be of a temporary character such as air in the fuel lines. However if the cause is of a more permanent nature than at the expiration of the predetermined time the unit is shut down. This is brought about due to an arm 75 of a reverse current time element having been gradually moved upward during motoring action until arm 75 engages contact 84' whereupon a circuit is established from wire 32', through arm 75, contact 84', wires 84, 84'', solenoid 19' and to the other line 3. Energization of solenoid 19' pulls back catch 16 to allow lever 13 to drop and shut off the fuel. At the same time arm 75 will have opened contact between spring 19 and its contact 18 to break the circuit through wire 20 for solenoid 23 thus causing the opening of switch 22 to stop the motoring of the generator. Switch 22 would normally tend to close when the motoring action starts due to relay 37, 38 opening switches 65, 66 all as will be described later.

In the second method of starting wherein the generator is used as a motor to drive the engine until it is started, assume that generating unit A is at rest and that the manual control is disconnected as by closure of air valve 8 and opening of switch 11. A switch 16' is then closed thereby energizing solenoid 23 to close switch 22. Upon closure of switch 22 current flows from battery 1 through series field 25 of battery booster 4 to a bus 24, thence through wire 26, across contacts 28 which have been closed by switch 22, starting resistance 30, protective resistance 31, wire 32, compound field 33, armature of generator 34, wire 32', reverse current time element 35, wire 36, current coil 37 of relay 38, wire 39, line 2 and back to battery 1.

Closing of switch 16' has also established a circuit from main 2 through wires 17 and 40, field resistance 41, movable contact arm 42, wire 43, across closed contacts 44, wire 47, shunt field 48 and wire 49 to line 3.

Closing of switch 22 as described above allows current to flow through armature of generator 34 which thus acts as a motor to rotate the engine E of generating unit A. As the speed of rotation of the motor or generator 34 increases, the voltage across same also increases until when it reaches a certain value more current is passed to the motor. The effect of this is to insure that the rotating parts of the engine generator have accumulated sufficient momentum before fuel is injected into the cylinder, otherwise if fuel was injected before this momentum was acquired the engine would not be able to carry over dead center against the explosion which occurs ahead of dead center. The compression reliefs will also remain open until this momentum is obtained thereby rendering it easier for the engine to come up to speed. To control this action a coil 51 is connected across the armature of generator 34 as by wires 32, 50, 52, 39, 36 and 32'. Hence the increasing motor voltage upon reaching a predetermined value causes solenoid 51 to close its contacts 51' and thus short circuit resistance 30 to permit more current to pass through generator 34, again increasing its speed. In practice this speed is brought up to about half that when running at generating speed. Resistance 31 remains in circuit with the generator whenever contacts 28 and 51' are closed. Closing of contacts 51' also closes contacts 53. This permits additional current to flow from line 2 (adjacent the battery) through wire 17, switch 16, wire 17', spring 19, wire 20, across contacts 53 to wire 54, oil pressure cut out 55, fuel control solenoid 56 and thermal cut out 57, which is closed whenever normal temperatures exist either in the cooling water or bearings, the circuit continuing down through wire 58 to line 3. When lubricating oil pressure is sufficient to close oil pressure cut out device 55, coil 56 is energized and arm 13 on the fuel pump control is raised against the tension of a spring 59 to engage a stop 60, the latch 16 having been previously pushed back manually so as to not interfere with automatic operation. Fuel then enters the cylinders whereupon engine of unit A starts and comes up to speed which will cause generator 34 to equal the voltage across busses 2 and 3 providing rheostat 41 is set to permit sufficient current to pass to the shunt fields 48 of generator 34. If a small amount of current is flowing through series field 33 in a direction normal for machine 34 to act as a generator, coil 37 of relay 38 will assist a shunt coil 61 to raise armature 62 and close its contacts. If, however, machine 34 does not come up to a speed sufficient to cause this action current will be flowing in the opposite direction through coil 37 and armature 62 will not raise. Closing of these armature contacts establishes a circuit through wire 64 to energize coils of switches 65 and 66 and close the same. Closing of switch 65 opens contacts 68 and deenergizes coil 23 of switch 22. This disconnects generator 34 from starting line 24, but at the same time the generator is connected with service bus 3 through wire 32 and switch 65.

Should engine of unit A at any time fail to operate, relay 38 permits its armature contacts to open because machine 34 will now act as a motor from constant potential mains 2 and 3. This

causes switches 65 and 66 to open, disconnecting machine 34 from main 3. Contacts 68 also close at this same time, causing switch 22 to close, whereupon machine 34 receives current again through resistance 31. This resistance is thus always in circuit with machine 34 when it is motoring or tending to motor. Should anything happen to generating unit A, such that it is suddenly stopped due for instance to seizure of a bearing, piston sticking, etc. resistance 31 prevents the armature of machine 34 from acting as a short circuit from main 2 to starting main 24. Relay 38 thus acts to control proper operation of the switching mechanism when machine 34 is acting as a generator and comes on the line but it also causes the generator to be disconnected if it is not operating properly to supply current to mains 2 and 3. The ballast resistance 31 is therefore a very essential feature as it limits the current that machine 34 can take when, under any conditions, it is taking current from mains 2 and 3 and it also prevents a short across armature of booster 4 if there is any overlapping in the actions of switches 22 and 65.

When switch 22 is closed a resistance 69 is shorted out of the shunt field circuit of machine 34. If rheostat 42 is set for the correct voltage when machine 34 is in parallel with the other machines B or C or battery 1 through booster 4, then when the machine is disconnected and allowed to motor as before the generator field will not build up to permit quite sufficient voltage to stabilize machine 34 and cause it to develop sufficient voltage to come on the line. By shunting out resistance 69, machine 34 is permitted to develop sufficient voltage to start a slight current flowing through series field 33 and back to bus 3 when being driven at the proper speed by engine 3 and with switch 65 open. This action causes relay 38 to close the contacts of its armature 62 whereupon switch 65 raises to cause switch 22 to fall open. With load current established through series field 33, generator 34 stabilizes its voltage and resistance 69 is in circuit when switch 22 opens. Machine 34 then develops the correct voltage over its normal range. Motor or generator 34 is usually a so called flat compound machine for the given variation in engine speed from no load to full load and generator 34 usually functions from about one-quarter load to full load or over load.

to establish a circuit through wire 80, switch 14 and contact spring 19 to wire 20 whereupon solenoid 23 is energized to close switch 22 after which the operations are the same as those previously described when starting the unit by motor action of the generator. If load demand increases beyond the capacity which it is desired to take from unit A, then relay 72 will become sufficiently energized to close and establish a circuit through wire 81 and switch 14B to the starting elements of unit B corresponding to those of unit A. Further increase in load demand similarly closes relay 73 and establishes a circuit through wire 82. If for any reason unit A should not start after a given length of time, hand 15 of reverse current time element 35 would, at expiration of that time and due to the motoring of the generator, have moved up into engagement with contact spring 19 and broken the circuit through wire 20, contacts 53 and wire 54, thereby breaking the circuit through oil pressure device 55 and solenoid 56 whereby fuel control arm 13 is pulled to its shut off position by spring 59. However, arm 15 upon breaking this circuit would establish a new circuit through wires 84 and 85, 25 82 and switch 14C to start unit C. Similarly if unit B fails to start, hand 15 of its reverse current time element will establish a circuit through wires 86, 87 and 82 to start unit C, assuming this unit is idle as it would be if unit A was in normal operative condition.

If desired switch 16' on the first unit can be left closed retaining this unit in service at all times and allowing units B and C to be brought on the line by relays 72 and 73 as load demand requires. This method obviates battery 1 or any other suitable source of standby current from carrying load except starting current or momentary fluctuations. Any unit may thus be selected to operate continuously, merely by closing its switch 16'.

Compressed air tank 6 is maintained automatically at proper pressure by air pump 7 which is operated by any usual pressure device on an electric controller 88. This may be of the usual standard construction for such compressors and regulators. It will be seen that by operating the valve 8 and switches 11 and 16' units may be started and placed on line by the operator without fear of error in handling switching mechanism. With the usual mechanism and switches if an en-

In place of manual operation of switches 16' for each unit, relays 71, 72 and 73 placed in the load line may be adjusted to start units A, B or C progressively as line load demands. Switches 74, 14B and 14C would be closed for this method of operation. Thus if the load demand should increase above a certain small amount which is normally carried by the battery alone, then relay 71 will be sufficiently energized and closed 70 battery discharge by vibrating relay 90 although it will be understood that my improved booster control can also be used, such being shown in my co-pending application, Serial No. 434,281. The 70 starting current passing through the series field of the booster assists it in maintaining the line voltage and compensates for the resistance drop of the battery when it is discharging during starting of a unit. When the generator has reached 75

normal voltage and has been placed on the line then battery booster functions to charge the battery on normal line voltage and causes battery to discharge into the line when line voltage becomes slightly below normal due to the generators being unable to meet the sudden momentary increase in current demand or a demand in excess of the generator capacity.

From the foregoing disclosure, it is seen that my improved arrangement is adapted to control the engines individually through manual operation in combination with automatic paralleling of the units or by a simple manipulation the complete automatic control can be brought into operation with manual means for disconnecting any one unit even though the automatic control should be set for a contrary action, there being the further advantage that no matter how the controls may be manipulated no danger exists as to short circuiting a unit across the line nor is excessive voltage variation created when a unit is started or stopped due to the current supply to the motor being shunted around the booster while yet obtaining all advantages of the booster.

Briefly summarized, the following are certain of the features of operation of my improved system.

Manual operation

1. Starting engine by opening air valve 8, and closing of switch 11 to close compression relief valves, and latching fuel lever 13 in its upper open position.
2. When engine comes up to speed switch 16' is closed, thereby closing switch 22, the speed governor controlling fuel supply.
3. Unit automatically connected to line only if generator voltage is normal.
4. If unit fails to start, then operator does not close switch 16'.
5. If unit becomes inoperative after being connected to line, generator acts as motor and arm 75 of reverse time element subsequently opens switch 22 to break current supply to motor, also pulling latch 16 from under fuel lever 13 to shut off fuel.

Semi-automatic operation

1. Switch 16' is closed, to supply current from battery to generator armature as though resistance 31 but without going through booster, current also being supplied to shunt field 48 across contacts 44, the motor thus rotating engine.
2. As generator speed increases more current is passed thereto due to relay 38 causing closure of contacts 51' to shunt resistance 30, protective resistance 31 remaining in circuit.
3. Engine speed increases until lubricating oil pressure is sufficient to close oil pressure device 55 whereupon coil 56 is energized and fuel arm 13 raised to start engine.
4. If engine comes up to speed, relay 38 will respond to corresponding increase of generator voltage which when normal will permit automatic connection of unit to line the same as in manual operation.
5. Failure of unit to start causes reverse current time element to open switch 22.
6. Ballast resistance 31 limits amount of current generator can take as for instance if engine abnormally stops when running.
7. Warming current for cold generator.

Full automatic operation

1. Line load relays 71, 72 and 73 substituted for manual operation of switches 16' for each unit by closing switches 74, 74B and 74C.

2. Automatic operations previously described then take place.

3. A unit can be kept on line by closure of its switch 16', allowing remaining units to be controlled by relays 72 and 73 assuming the first unit to be continuously operated.

It will of course be understood by those skilled in the art that from the foregoing disclosure various changes may be made without departing from the spirit of my invention as set forth in the appended claims.

I claim:

1. The combination in a generating system for supplying a main line, comprising a plurality of units each having a generator driven by a Diesel engine, means for starting the engine of each unit by compressed air, a manually operable switch for each unit, the switch of a unit that is started being actuated by the operator when the unit approaches normal speed, and means for automatically connecting the generator of said unit to the line after said switch is actuated and the generator voltage is normal.

2. The combination in an electric generating system for supplying a main line, comprising a plurality of units each having a generator driven by a Diesel engine, means for starting the engines, means whereby during starting of an engine its generator is substantially disconnected from the line but after the engine is started the generator is connected to the line to supply generated current thereto, and means for automatically disconnecting a unit from the line in case the unit gets out of order.

3. The combination in an electric generating system for supplying a main line, comprising a plurality of units each having a generator driven by a Diesel engine, means for starting the engines, means whereby during starting of an engine its generator is disconnected from the line but after the engine is started the generator is connected to the line, and means whereby a unit which is connected to the line and subsequently becomes inoperative is disconnected automatically after the inoperative condition has existed for a predetermined time interval.

4. The combination in an electric generating system for supplying a main line, comprising a plurality of units each having a generator driven by a Diesel engine, means for starting the engines, means whereby during starting of an engine its generator is disconnected from the line but after the engine is started the generator is connected to the line, and means whereby upon subsequent failure of unit its generator receives current from the line to act as a motor to drive the engine for a given length of time whereupon the unit is automatically disconnected from the line and stopped.

5. The combination set forth in claim 4 further provided with a fuel supply control for the engines, and means whereby the automatic disconnecting means also stops the fuel supply to the engine.

CHESTER F. STRONG. 70
